WORK TABLE FOR SKIVING MACHINES

Edwin H. Beck, Lemay, Mo., assignor to Manufacturers Supplies Co., St. Louis, Mo., a corporation of Missouri

Application May 31, 1957, Serial No. 662,926

2 Claims. (Cl. 69—9.5)

This invention relates to leather skiving machines, and more particularly to machines of the type having a bell type of cylindric cutter.

It will be understood that such a skiving machine generally comprises a base or housing containing a cup-like cutting knife, which is formed with a back and a cylindric cutting portion projecting from the back, the end portion of the cylinder being ground to a bevel cutting edge. The knife rotatably is mounted by its back on a horizontal axis so that only a slight segment of the cylinder projects above the top of the housing, there being an opening in the top of the housing for this purpose. Usually, a feed roller is mounted beneath the cutting edge and a presser foot above the feeder in order to feed the leather against the rotating edge of the knife. The machine is also provided with a knife-sharpening device within the housing so that the cutting edge can be ground from time to time. After grinding, the knife is readjusted toward the feeder, hence an increasingly large gap is opened at the back of the knife through the opening in the housing.

In order to prevent small pieces of work from falling into this gap, it has been proposed that a shield be fixed to the housing so as to extend over the knife substantially to its cutting edge. The disadvantage with such a shield is it creates a bulge over the knife, which interferes with the movement of the work as it leaves the feeder. Also, small particles sometimes tend to accumulate between the cylindric portion of the knife and the overlying shield and develop a braking action on the cutter.

Accordingly, an object of this invention is to provide improved means for closing the gap in the housing at the back of the knife, while leaving the knife relatively unobstructed so that the work may flow over it with a minimum of interference. Another object of the invention is to provide a convenient attachment for the above purpose, which attachment is also adapted to receive a work table extension so that the flat area adjacent the knife can be conveniently enlarged. This is advantageous because it is often necessary to swing a relatively large piece of leather about a vertical axis at the presser foot, as when skiving curved edges.

Various other objects of the invention will be apparent in the detailed description, but briefly, I provide a cover plate, which is secured against the front wall of the housing so as to extend over the top surface thereof. The top portion of the plate has a large recess formed to accommodate the knife where it projects upwardly from the housing, and the portion of the plate behind the knife carries a sliding guard, which is movable toward and away from the back of the knife.

As the cylindric portion of the knife is shortened by grinding, the knife is readjusted toward the feeder, and the sliding guard is also moved forwardly against the back portion of the knife in order to close the gap that would otherwise occur. A simple friction fit between the guard and cover plate will normally be sufficient to hold it in position but the guard may be readily opened to afford access to the space behind the knife.

2

In addition, the invention contemplates the provision of a table-extension which is adapted to be secured to the front portion of the cover plate by a depending support and which otherwise projects horizontally with respect to the work table from the front of the machine. The edges of the cover plate and work table extension are adapted to fit closely with one another so as to assure a smooth uninterrupted surface. Also, the depending support for the table may have a pin-and-hole interlocking cooperation with the depending portion of the cover plate, thereby to lock the work table in proper position. With this arrangement, it is a relatively simple step to provide a series of work table extensions to fit varying requirements of the job.

Other features of the invention will be in part apparent from and in part pointed out in the following detailed description taken in connection with the accompanying drawings, in which:

Fig. 1 is an oblique view of a portion of a skiving machine illustrating the knife-gap closure accessory of this invention;

Fig. 2 is a vertical section taken generally on the line 2—2 of Fig. 1;

Fig. 3 is another vertical section taken generally on the line 3—3 of Fig. 1 but further showing the work table extension; and

Fig. 4 is a top plan view, parts being broken away, showing the cover plate and work table extension in assembly.

Referring to Fig. 1 of the drawings, there is shown a portion of a skiving machine of the type having a so-called bell knife. Such a machine includes a base housing 1 containing certain mechanism (the details of which are not significant to this invention). A knife generally designated 3 is mounted within the housing and is adapted to be rotated about a horizontal axis by a suitable power unit. The knife is formed with a back wall 5 so that it can be secured to a horizontal shaft, which is also adapted to permit axial adjustment of the knife. The cylindric portion 7 of the knife projects from the back toward a feed roller partially shown at 9. The feed roller is rotary about a horizontal axis transverse to that of the knife so as to feed work against the cutting edge 11.

A typical skiving machine generally includes the grinding device (not shown) within the housing, which can be actuated by the operator from time to time so as to maintain a keen edge on the knife. The work otherwise is guided against the knife by a presser foot 13 adjustably carried upon an arm 15, which projects upwardly and is supported from the back of the housing.

The work is guided under the presser foot from the left side as viewed in Fig. 1, whereupon the feed roller feeds the work against the cutting edge. The presser foot may be at an angle to the knife in order to provide a beveled skive along an edge of the work, which edge of the work moves from left to right as viewed in Fig. 1. In other words, after being skived, the work moves over the top cylindric portion 7 of the knife and across the top of the housing. It will be apparent that a portion of the knife projects upwardly through an opening in the housing, and as the knife edge is ground away from time to time, the entire knife is advanced toward the feeder so that the cutting edge will always be adjacent the feed roller 9. This axial adjustment of the knife, in turn, results in an increasingly large gap at its back 5, which is undesirable in certain classes of work since the small pieces could fall into the housing.

In order to overcome this disadvantage, I provide a knife closure accessory generally designated 17. A cover plate is curved to provide a depending portion 19 for fastening against the front of the housing 1 and a portion 21 ex-

tending over the top of the housing. The depending portion 19 has a pair of slots 21 receiving knurled screws 23. The top portion 21 of the plate is cut with a large recess 25 which surrounds the knife and permits it to project upwardly as illustrated. In other words, the cylindric portion 7 of the knife is exposed at the top, hence the cover plate does not interfere with movement of the work. The back edge of the slot 25 is sufficient to accommodate the knife in its new condition of maximum length, but as the knife is worn down and moved forwardly, a gap will be opened.

This gap is adapted to be closed, however, by a sliding guard 27, which has beveled edges 29 received within overhanging or dovetail guides 31 at opposite sides of the guard. The edge 33 of the guard adjacent the knife is suitably shaped to conform with the knife to substantially close any gap. Also, a finger notch 35 is provided in the guard to facilitate its adjustments toward and away from the knife. In use, the guard is adjusted after each adjustment of the knife, but if desired, the guard may be drawn back to afford access with the space adjacent the knife.

Referring now to Figs. 3 and 4, there is shown an extension which cooperates with the knife guard device 13. This extension device includes a flat table portion 41 having an inner edge 43 conformed to fit closely with the upper flat portion 21 of the guard assembly. The table 41 is secured by a depending support 45, which is fastened against the depending portion 19 of the above cover plate. For example, the portion 19 may be provided with a pair of small pin holes 47 which receive aligning pins 49 secured to the support 45 of the work table. A knurled screw 51 is then received through an opening in the table support 45 and is threaded into a tapped hole 53 in the cover plate. With this arrangement, it is contemplated that there will be an assortment of table sizes in order to provide for various needs of users.

It will be understood, for example, that some relatively large pieces of leather may have complicated curved edges which must be beveled or skived and since the edges of the work should move at right angles to the edge 11 of the knife, it may be necessary to rotate or pivot work about a vertical axis at the presser foot as it is moved therebeneath. With present skiving machines, the working area is rather small or substantially non-existent,

hence the skiving of such large pieces is often difficult. On the other hand, the provision of a table extension affords a large area and clearly simplifies this type of operation.

From the foregoing description, it is apparent that those skilled in the art will understand the structure, function and mode of operation of the invention herein disclosed, and appreciate the advantages thereof. Although one embodiment has been disclosed in detail, it is to be understood that the invention is not limited thereto, but the drawings and description thereof are to be understood as being merely illustrative. It is realized that many modifications and variations will present themselves to those skilled in the art without departing from the spirit of this invention or the scope thereof as set forth in the appended claims.

Having thus described the invention, what is claimed and desired to be secured by Letters Patent is:

1. A work table device for the bell knife of a leather skiving machine of the type described, comprising a cover plate having a top portion adapted to overlie the work table adjacent said knife and a depending portion adapted to be secured against the front of the housing, and a guard plate slidably mounted on said top portion of the cover plate for movement toward and away from the knife thereby to close a gap adjacent the knife.
2. In a skiving machine of the character described, having a housing, a bell-type of knife projecting partially through an opening in the top of the housing, the knife having a cylindric surface which is shortened in use and which is adjustably moved from time to time, thereby to open an increasingly large gap through the housing adjacent the knife; the improvement comprising a cover plate having a top surface overlying the housing of the machine and recessed to accommodate the knife, said cover plate having a portion depending over and secured to the front of the housing, and a guard member slidably mounted on the top of the cover plate for sliding movement over said opening toward and away from the knife, thereby to permit closure of the gap as the knife is shortened in use.
